Primary Examiner—M. N. Pandozzi
Attorney, Agent, or Firm—Kirschstein et al.**[57] CLAIM**

The ornamental design for a beverage dispenser, as shown and described.

DESCRIPTION

FIG. 1 is a front, top and left perspective view of a beverage dispenser showing my new design; and,

FIG. 2 is a rear, top and left perspective view thereof. The front wall which is partially hidden by nozzles follows the contours shown. The right side is symmetrical with the left side.
